UNITED STATES PATENT OFFICE

124,405

DESIGN FOR A TONE CABINET

Laurens Hammond, Chicago, Ill.

Application October 26, 1940, Serial No. 96,105

Term of patent 14 years

To all whom it may concern:

Be it known that I, Laurens Hammond, a citizen of the United States and resident of Chicago, in the county of Cook and State of Illinois, have invented a new, original, and ornamental Design for a Tone Cabinet, of which the following is a specification, reference being had to the accompanying drawing, forming part thereof.

I claim:

The ornamental design for a tone cabinet, as shown.

LAURENS HAMMOND.
